RANGE BACKGUARD OR THE LIKE

Robert L. Gault, Hillsdale, Mich., assignor to Westinghouse Electric Corporation, East Pittsburgh, Pa., a corporation of Pennsylvania

Filed Sept. 18, 1964, Ser. No. 81,781

Term of patent 14 years

(Cl. D81—25)

FIGURE 1 is an isometric view of a range backguard embodying my invention;

FIG. 2 is a sectional view, taken along the line II-II of FIG. 1, looking in the direction indicated by the arrows;

FIG. 3 is a view similar to FIG. 1 of a range backguard embodying a modification of my invention; and

FIG. 4 is a sectional view, taken along the line IV-IV of FIG. 3, looking in the direction indicated by the arrows.

The end not shown in FIG. 1 is similar in appearance to the end therein shown.

The end not shown in FIG. 3 is similar in appearance to the end therein shown.

The dominant features of my design reside in the parts shown in the full lines.

I claim:

The ornamental design for a range backguard or the like, substantially as shown and described.
